APPARATUS FOR THE CONTROL OF
HIGHWAY CROSSING SIGNALSBranko Lazich, Edgewood, Pa., assignor to The
Union Switch & Signal Company, Swissvale,
Pa., a corporation of PennsylvaniaApplication March 31, 1933, Serial No. 663,729
Renewed August 30, 1935

23 Claims. (Cl. 246—130)

My invention relates to apparatus for the control of highway crossing signals, and particularly to apparatus for providing a uniform period of warning at the highway.

5 An object of my invention is the provision of apparatus controlled by a train approaching a highway intersection for measuring the speed of the train, and for also determining the acceleration or deceleration of the train. The starting 10 of the operation of the highway signal is controlled in accordance with the measured speed and determined condition of acceleration or deceleration in such a manner that substantially an equal interval of operation of the highway signal 15 before the train reaches the highway is obtained for all trains. A further object of my invention is the provision of apparatus to assure operation of the highway crossing signal in case of a following train entering the approach or measuring 20 track section before the first train has passed the crossing, and to prevent operation of the apparatus in the case of reverse running. A still further object of my invention is the provision of apparatus to check the operating condition of 25 the speed measuring devices. Other objects and features of my invention will appear as the specification progresses.

I will describe one form of apparatus embodying my invention, and will then point out the 30 novel features thereof in claims.

The accompanying drawing is a diagrammatic view of one form of apparatus embodying my invention.

Referring to the drawing, the reference characters l and l^a designate traffic rails over which traffic normally moves in the direction indicated by an arrow and which are intersected by a highway H shown at the right-hand end of the drawing. At the highway intersection there is located 40 a highway crossing signal S . The signal S is indicated on the drawing conventionally as a combined audible and flashing light highway crossing signal. It will be understood, however, that my invention is not limited to any specific 45 form of highway signals and any of the standard signals may be used. The signal S in the drawing will serve to indicate a highway signal normally inactive, and which is rendered active to display a warning to highway users whenever a 50 train approaches the intersection. The operation of the signal S is governed by a mechanism indicated by the reference character M^3 , which mechanism is effective to render the signal S active in response to current supplied thereto.

55 The traffic rails l and l^a are divided by the

usual insulated rail joints into four track sections $A-B$, $B-C$, $C-D$ and $D-E$, which track sections are traversed successively by a train approaching the highway H when moving in the normal direction of traffic. Each track section is provided with a track circuit comprising a track battery 3 , and a track relay R with an exponent designating its location. Interposed between the track relay R^A and rail l for the track section $A-B$ is a front contact 4 of the track relay R^B , and in like manner a front contact 5 of relay R^C is included in the connection of the track relay R^B with the rail l of the section $B-C$. The function of these front contacts will become apparent as the description proceeds. 15 For the purpose of this description, I shall speak of the sections $A-B$ and $B-C$ as measuring sections, the section $C-D$ as an operating section, and the section $D-E$ as a positive operating section. 20 As will appear hereinafter, the speed of a train as it traverses the measuring sections $A-B$ and $B-C$ is measured, and the acceleration or deceleration of the train is determined. The highway crossing signal S is set into operation as the train traverses the operating section $C-D$ in 25 accordance with the measured speed and the condition of acceleration or deceleration, the time of starting of the operation of the signal being made such as to insure substantially an equal interval of operation before the train reaches the highway 30 for all trains. Positive operation of the highway signal S takes place during the time a train occupies the track section $D-E$ irrespective of whether the train is moving or not.

In order to more easily understand the operation of the apparatus of my invention, I shall assume the maximum speed for all trains to be 35 90 miles per hour, and that substantially 20 seconds exhibit of the highway crossing signal will be obtained before the train reaches the highway. 40 A train travelling at 90 miles per hour will move approximately 2640 feet in 20 seconds, and consequently, the combined length of sections $C-D$ and $D-E$ is made 2640 feet in length. Preferably the section $D-E$ is made short, say, 300 feet 45 in length, and hence the operating section $C-D$ is 2340 feet in length. For reasons to appear hereinafter the two measuring sections $A-B$ and $B-C$ are preferably equal in length and their combined length equal to the combined length 50 of sections $C-D$ and $D-E$. That is to say, the measuring sections will be each 1320 feet in length. It will be understood, of course, that my invention is not limited to the above lengths for the track sections, and the length of these sev- 55

eral sections will be arranged to suit each individual location, and to suit different maximum speeds and different intervals for operating the highway crossing signal.

5 As here shown the speed measuring device comprises a shaft 6 shown schematically by a dotted line, and on which are rigidly mounted three circuit controlling cams 7, 8 and 9. Shaft 6 is driven by a motor M² through the medium 10 of a suitable train of gears designated by the reference characters 10 and 11. The shaft 6 and the cams 7, 8 and 9 normally occupy the position in which they are illustrated in the drawing, and are arranged to be at times moved 15 away from this normal position in a clockwise direction toward a reverse position by the rotation of the motor M² in one direction, the full reverse position being a little less than one revolution. At other times they are restored to the normal 20 position by reversing the direction of rotation of motor M².

A centrifuge N is operatively connected with the motor M², and this centrifuge governs a circuit controlling contact C6 in such a manner that the contact C6 rests in engagement with contacts 12 and 13 as long as the motor M² is not operated, and is raised into engagement with contacts 14 and 15 when the motor is rotating at a speed which exceeds a predetermined value. 25 The centrifuge N is provided to check the normal position and operation of the motor M² as will appear hereinafter.

30 Associated with the speed measuring device is a relay SR which is slightly slow releasing in character. Relay SR is normally energized over a circuit extending from the terminal X of a convenient source of current such as a battery not shown, through front contact 16 of the track relay R^C, a circuit controller C8 operated by the cam 7, wire 17, winding of relay SR and to the opposite terminal Y of the same source of current. Relay SR governs the operation of the highway crossing signal S as will later appear, and it is made slightly slow releasing to bridge 35 the time interval required for the motor M² to reverse its direction of rotation.

The circuit controlling cam 7 is adapted to 40 control five circuit controllers C2, C3, C8, C9 and C10. Circuit controllers C8, C9 and C10 are normally closed and are opened only after the cam 7 has been operated in a clockwise direction to the reverse position, that is, approximately a full revolution, where a member 18 drops into the depression 19 on the cam 7. Circuit controller C2 is normally closed and is opened immediately after cam 7 is moved in a clockwise direction from the normal position and a member 20 is raised out of the depression 19. The controller C3 is normally open, and is closed as member 20 is lifted out of the depression 19. The cam 9 is provided with a contact segment 23 of a predetermined length and which in the normal position of the cam engages the contact member 24 of a controller C4. The parts are so proportioned and adjusted that the contact member 24 remains in engagement with the contact segment 23 for approximately 20 seconds of operation of the cam 9 in the clockwise direction. The cam 8 is provided with a contact segment 21 which normally engages the contact member 22 of a controller C5. The contact segment 21 is preferably made equal in length to the contact segment 23 on the cam 9. The 45 function of these controllers C2, C3, C4, C5, C8, 50

C9 and C10 will appear when the operation of the system is described.

The acceleration-deceleration measuring device comprises a shaft 25 indicated in the drawing by a dotted line, and on which are rigidly mounted a cam 26 and a contactor 27. The cam 26 and contactor 27 normally occupy the position illustrated in the drawing and are adapted to be driven at times away from that position either in the clockwise direction 5 or in the counter-clockwise direction by a constant speed motor M¹ driving the shaft 25 through the medium of a train of gears indicated by the reference characters 28 and 29. At times the motor M¹ is rotated in a direction to drive 10 the shaft 25 in a counter-clockwise direction, at other times the motor M¹ is rotated in the opposite direction and the shaft 25 is driven in a clockwise direction, and at still other times the motor M¹ is operated in a direction that brings 15 the cam 26 and contactor 27 to their normal position. The cam 26 is adapted to operate a pole-changing circuit controller C1 in such a manner that as the shaft 25 is rotated counter-clockwise from the normal position, an operating 20 member 74 drops into a depression 75 and the back contacts 53 and 54 of controller C1 are closed. At such time as the cam 26 is operated clockwise from the normal position, the member 74 is lifted by a raised portion 76 and the front 25 contacts 51 and 52 of controller C1 are closed. In the normal position of the cam 26 all contacts of controller C1 are open. One end of the contactor 27 is adapted to make contact with a contact segment 30, and its other end normally 30 makes contact with a centrally located contact button 31 of a variable resistance unit comprising two resistors R² and R³. Resistors R² and R³ are preferably arranged in steps and are provided with contact buttons with which the 35 contactor 27 will successively engage as it is rotated from the normal position. As will appear later, the centrally located button 31 constitutes what I shall call a constant speed point and which point is here identified by the reference character 40 CP. The resistor R² to the right of the constant speed point CP constitutes a compensating resistance for deceleration, and the resistor R³ to the left of the point CP constitutes a compensating resistance for acceleration. It follows, 45 that when the contactor 27 rests on the contact button 31 at the constant speed point CP, the full resistor R² is in circuit between the contact segment 30 and a terminal 65. When the shaft 25 and hence contactor 27 are rotated counter-clockwise, the contactor 27 is moved along the successive contact buttons of resistor R³ and the successive portions of resistor R³ are added to the resistor R² in the connection between the segment 30 and the terminal 65. When the shaft 50 25 is rotated clockwise, the contactor 27 is moved along the successive contact buttons of resistor R² and portions of the resistor R² are cut out of circuit, making the resistance between the contact segment 30 and the terminal 65 something 55 less than the full resistance of resistor R². As will later appear, a third resistor R¹ is associated with the two resistors R² and R³ and the resistance of the resistor R¹ is preferably made equal to that of the full resistance of the resistor R². 60

A stick relay R^S is included in the equipment and this relay R^S is provided with an energizing circuit which can be traced from the terminal X of the current source through wire 82, front contact 32 of track relay R^C, wire 33, controller C2, 65

wire 34, winding of relay R^S, wire 35, front contact 36 of track relay R^P and to the opposite terminal Y of the current source. A stick circuit for this relay R^S extends from the terminal X of the current source through controller C9, its own front contact 37, winding of the relay R^S and thence as before traced to the terminal Y.

Referring to the drawing, the operation of my system can be explained as follows: As long as no train occupies any of the track sections, the track relays R^A, R^B, R^C and R^P are all picked up and both motors M¹ and M² are inactive, and both the speed measuring device and the acceleration-deceleration measuring device are in the normal position, that is, the position shown in the drawing. The mechanism M³ is also deenergized and signal S is inactive. A train approaching the highway H from the left first enters the track section A—B and shunts the track relay R^A. As relay R^A is released, current is supplied to both motors M¹ and M² and these motors rendered active. To be explicit, the field winding MF¹ of motor M¹ now receives current from the X terminal of the source of current over wire 82, back contact 38 of relay R^A, wire 39, field winding MF¹, a second back contact 40 of relay R^A, wires 41 and 42, front contact 43 of the stick relay R^S and to the terminal Y of the current source. The armature 44 of motor M¹ is supplied with current from the terminal X of the current source over wire 83, front contact 45 of track relay R^B, front contact 46 of track relay R^C, back contact 47 of track relay R^A, controller C10, armature 44, back contact 48 of relay R^A, front contact 49 of relay R^C, front contact 50 of relay R^B, wire 42 and front contact 43 of relay R^S to the opposite terminal Y of the current source. The energization of the armature 44 by this circuit is such as to cause the motor M¹ to be rotated in a direction that rotates the shaft 25 in a counter-clockwise direction and at a predetermined rate of speed. Consequently, contactor 27 is now moved to successively cut in resistance steps of the compensating resistor R³. After a slight movement of shaft 25, the cam 26 will shift the controller C1 to close the back contacts 53 and 54, the purpose of which will be later pointed out.

The field winding MF² of motor M² is now energized by current supplied from the terminal X of the current source over wire 82, back contact 38 of relay R^A, wires 39 and 55, field winding MF², wire 67, resistor R¹, front contact 56 of relay R^C, wire 57, back contact 40 of relay R^A, wires 41 and 42 and thence over front contact 43 of relay R^S to the terminal Y. The armature 58 of motor M² is supplied with current from battery terminal X over front contact 16 of relay R^C, controller C8, wires 17 and 59, back contact 60 of relay R^A, armature 58, back contact 61 of relay R^A, front contact 62 of relay R^C and thence over the front contact 43 of relay R^S to the terminal Y. The energization of the armature 58 by this circuit just traced is such as to cause the motor M² to rotate in a direction to drive the shaft 6 in the clockwise direction at a predetermined rate of speed. It follows that the cams 7, 8 and 9 are rotated in a clockwise direction, and the centrifuge N is operated to raise the contact C6 out of engagement with the contacts 12 and 13 but not far enough to engage the contacts 15 and 14.

It is clear from the foregoing description that as long as the train occupies the section A—B, the acceleration-deceleration measuring device is

driven in a counter-clockwise direction at a predetermined rate, and that the speed measuring device is driven in a clockwise direction at a predetermined rate. The angular distance the contactor 27 of the acceleration-deceleration device, 5 and the cams 7, 8 and 9 of the speed measuring device are rotated will depend upon the time it takes the train to pass over the section A—B.

As the train advances into the second measuring section B—C, the track relay R^B is shunted and that relay is released. The opening of the front contact 4 of relay R^B causes relay R^A to be held deenergized as long as the train occupies the section B—C. With relay R^A held down, the previously traced circuit for the field winding MF¹ 15 of motor M¹ remains closed at the back contacts 38 and 40 the same as when the train occupied the section A—B. Track relay R^B upon releasing opens the front contacts 45 and 50 and closes the back contacts 63 and 64 to pole change 20 the armature circuit for the motor M¹ as will be readily understood by an inspection of the drawing. Reversing the direction of the current flow in the armature 44 of the motor M¹ reverses the rotation of that motor and the shaft 25 of the 25 acceleration-deceleration measuring device is now driven in a clockwise direction, the rate of rotation remaining the same as the rate at which it was rotated in the counter-clockwise direction. As previously stated, the track section A—B is 30 made the same length as the section B—C and since the speed of motor M¹ is the same in both directions of rotation, it is clear that if a train travels over both sections A—B and B—C at a constant speed, the contactor 27 travels in the 35 clockwise direction while the train passes over section B—C, the same angular distance as it travelled in the counter-clockwise direction while the train is passing over section A—B, and it is returned to the constant speed point CP as the 40 train reaches the outgoing end of section B—C. If, however, the train is not running at a constant speed, but is accelerating, contactor 27 would be driven for a longer time in the counter-clockwise 45 direction during the time the train was passing over section A—B, than it is driven in the clockwise direction while the train is passing over the section B—C, and, consequently, contactor 27 would be at some point to the left of the constant speed point CP when the train reaches the outgoing end of section B—C. As a result, a certain portion of resistor R³ is inserted with resistor R² in the connection between the terminal 65 and the segment 30. On the other hand, if the train is slowing down, the contactor 27 would be driven 50 in the clockwise direction for a longer period while the train is passing over section B—C, than it would be driven in the counter-clockwise direction while the train is passing over section A—B and contactor 27 is at some point to the right 55 of the constant speed point CP when the train reaches the outgoing end of section B—C. Under this condition, a certain portion of resistor R² would be cut out of the connection between the terminal 65 and the segment 30. It follows, therefore, that the resistance between the terminal 55 and the segment 30 is in accordance with the acceleration or deceleration of the train, being equal to that of resistor R² when the speed is constant and there is neither acceleration nor deceleration, being equal to resistor R² plus a corresponding portion of resistor R³ when the train is accelerating, and being equal to a corresponding portion of resistor R² only when the train is decelerating. 60

The shunting of the track relay R^B causes no change in the circuit for the field winding $MF2$, or in the circuit for the armature 58 and hence, motor M^2 continues to drive the shaft 6 in the 5 clockwise direction while the train occupies the section $B-C$ the same as when in the track section $A-B$. If a train is travelling at the maximum speed of 90 miles per hour, it will require approximately 20 seconds for it to pass over the 10 2,640 feet of the two measuring sections, and consequently, the cam 9 will not be rotated far enough to open the controller $C4$ before the train reaches the outgoing end of section $B-C$. In the event the train passes over the measuring 15 section at some speed less than the maximum speed, say for example, 60 miles per hour, it would consume approximately 30 seconds before it reaches the exit end of the section $B-C$ and the cam 9 would have rotated in the clockwise 20 direction for a corresponding period of time and the controller $C4$ would have been opened for approximately the last 10 seconds of this period. In the event the speed of the train was only 30 miles per hour, it would consume approximately 25 60 seconds in passing over the two measuring sections and controller $C4$ would have been open for approximately the last 40 seconds of that period. It follows that the angular distance of rotation of the cams 7 , 8 and 9 is in accordance 30 with the speed of the train in the measuring sections, and the length of time the controller $C4$ is open during this operation is inversely proportional to the average speed of the train.

To sum up thus far, when a train maintains 35 substantially a constant speed as it travels over the two measuring sections $A-B$ and $B-C$, the contactor 27 is set at the constant speed point CP ; if the train is accelerating, contactor 27 is set at a corresponding point to the left of the 40 constant speed point CP inserting a portion of resistor R^3 with resistor R^2 in the connection between the terminal 65 and the segment 30 ; and if the train is decelerating, contactor 27 is set at a corresponding point to the right of the 45 constant speed point CP and a portion of resistor R^2 is cut out of the connection between terminal 65 and the segment 30 . In all cases the speed measuring device is constantly driven in a clockwise direction during the entire time the 50 train is passing over the two measuring sections, with the result that the angular distance that the cam 9 has been rotated corresponds to the average speed of the train.

The train upon entering the operating section 55 $C-D$ shunts the track relay R^C and that relay is released. The front contact 5 in the circuit for relay R^B is now open and hence both track relays R^B and R^A remain down as long as the track relay R^C is deenergized. Opening of the 60 front contacts 46 and 49 of relay R^C , removes current from the armature circuit of motor M^1 and operation of the acceleration-deceleration 65 measuring device is stopped. The result is that contactor 27 is stopped as soon as the train enters the operating section $C-D$, and is left in the position to which it has been operated in the manner described above. Opening of the front contact 56 of relay R^C and the closing of the back contact 66 transfers the circuit for the field winding $MF2$ of motor M^2 from the resistor R^1 to the circuit through the resistors R^2 and R^3 . The circuit for the field winding $MF2$ now 70 includes battery terminal X , wire 82 , back contact 38 of relay R^A , wires 39 and 55 , field winding $MF2$, wire 67 , terminal 65 , resistors R^2 and

R^3 in accordance with the position of contactor 75 27 , segment 30 , back contact 66 , wire 57 , back contact 40 , wires 41 and 42 and front contact 43 of relay R^S to the terminal Y . As relay R^C is released, the opening of the front contacts 16 and 62 and the closing of the back contacts 68 and 69 pole changes the armature circuit for motor M^2 and hence the direction of motor M^2 is reversed. To be explicit, the circuit for the armature 58 now extends from the terminal X over 10 back contacts 68 and 61 , armature 58 , back contact 60 , wire 59 , controller $C3$ which was closed as soon as cam 7 was moved from its normal position, wire 70 , back contact 69 and the front contact 43 of relay R^S to the terminal Y . The 15 rotation of the motor M^2 having been thus reversed, the shaft 6 is driven in a counter-clockwise direction from the point to which it has been advanced while the train occupied the measuring sections back toward the normal position and the 20 speed of motor M^2 will be in accordance with the position of the contactor 27 . In the case the speed of the train remained constant as it traversed the sections $A-B$ and $B-C$ and contactor 27 is at the point CP , the full resistance of resistor R^2 is inserted in the circuit for the field winding $MF2$, and as this resistance is equal to 25 that of the resistor R^1 , the rotation of motor M^2 will be at the same rate for the reverse direction as it was for the normal direction. In the event 30 the train was accelerating and the contactor 27 is set at some point to the left of the constant speed point CP , the resistance in the field circuit is equal to resistor R^2 plus a portion of resistor R^3 and the energization of the field winding 35 $MF2$ is correspondingly decreased so that the speed of motor M^2 during its reverse operation is increased proportionally. That is, the increase in the speed of motor M^2 is in direct proportion to the acceleration registered by the contactor 40 27 . In the event the train was slowing down as it traversed the sections $A-B$ and $B-C$, and the contactor 27 is set at some point to the right of the constant speed point CP , the resistance in the circuit to the field winding $MF2$ is something less than that of resistor R^1 with the result that the energization of the field winding $MF2$ is increased and the speed of the motor M^2 correspondingly decreased. That is to say, 45 the decrease in the speed of the motor M^2 during 50 its reverse operation is directly proportional to the deceleration of the train.

When relay R^C was shunted by the train entering the operating section $C-D$, the opening of the front contact 16 removed energy from the 55 winding of relay SR and that relay released at the end of its slow release period to close its back contact 71 . As soon as the cam 9 is rotated back toward its normal position, in the manner just described, far enough to bring the contact segment 23 into engagement with the contact member 24 , current is supplied to the mechanism M^3 of the highway signal S . This operating circuit extends from the terminal X of the current source over line wire 72 , back contact 71 of relay SR , contact $23-24$ of controller $C4$, line wire 73 , mechanism M^3 of signal S and thence to the opposite terminal Y . In the event the train is travelling at the maximum speed of 90 miles per hour and the controller $C4$ has not been opened, the mechanism M^3 is energized as soon as the relay SR releases and the signal S is displayed substantially the full time required for the train to pass over the operating sections $C-D$ and $D-E$ and the 20 seconds operation of the signal before the train 75

reaches the highway H is provided. In the case the train is travelling at a lower speed than the maximum speed and its speed remains substantially constant throughout the measuring sections, the speed measuring device is restored to its normal position at the same rate as it was rotated away from its normal position and controller C4 is not closed until some time after the train has entered the operating section C—D, the 5 delay being such as to provide substantially 20 seconds operation of the signal S for all constant speeds. In the case the train is accelerating as it passes over the measuring sections, the cam 9 is rotated back toward its normal position at 10 a speed sufficiently increased over the rate at which it was driven away from its normal position as to close the controller C4 soon enough to provide the 20 seconds operation of the signal S before this accelerating train reaches the highway. 15 That is to say, the resistance inserted in the circuit to the field winding MF2 by the operation of contactor 27 will so increase the reverse operation of motor M² as to compensate for the acceleration of the train. In the case the train 20 is slowing down as it passes over the measuring sections, the contactor 27 functions to decrease the resistance in the field winding MF2 and the reverse operation of the motor M² is slowed down sufficiently as to assure substantially the same 20 seconds operation of the signal S before the train reaches the highway. In other words, when 25 the speed of the train remains substantially constant, the speed measuring device so functions for all speeds as to provide substantially the same 20 seconds operation of the highway signal. The 30 acceleration-deceleration measuring device so governs the rate of speed of the speed measuring device during its reverse operation as to compensate for acceleration or deceleration and still 35 assure the same 20 seconds operation of the highway crossing signal.

During the time the train occupies the short track section D—E positive operation of the highway signal S is accomplished. When the train 40 enters the section D—E, the relay R^D is shunted and its back contact 71 is closed. The closing of 45 the back contact 71 completes an operating circuit easily traced for supplying current to the mechanism M³ of the highway signal. It follows 50 that the signal S will be continuously displayed as long as the train occupies the section D—E irrespective of whether it is moving or not. As 55 stated above, this section D—E is short, and is preferably made only just long enough to assure positive operation of the signal S should a train stop at the highway.

Shunting of the track relay R^D also opens the front contact 36 in the stick circuit for the relay R^S causing that relay to become deenergized. 60 Relay R^S upon releasing closes a back contact 78 to complete a shunt path around the back contact 65 69 of relay R^C and the front contact 43 of relay R^S in the armature circuit for the motor M². Consequently, the reverse operation of motor M² is continued after the train enters the section 70 D—E until the speed measuring device has been restored to its full normal position and controller C3 opened by the member 20 dropping into the cam depression 19. The contact segment 21 of 75 the cam 8 is preferably made of the same length as the contact segment 23 of cam 9. Thus, when the speed measuring device is restored toward its normal position after the train has entered the operating sections, far enough to close the controller C4 and start operation of the highway sig-

nal S, the controller C5 is also closed and the motor M¹ is energized to restore the acceleration-deceleration measuring device to its normal position. The circuit for energizing the field winding MF1 of motor M¹ remains the same as previously traced except that the connection to the Y terminal of the current source is now over the back contact 69 of relay R^C and the back contact 78 of relay R^S instead of over the front contact 43 of relay R^S. Current is now supplied to the armature 44 of motor M¹ over the circuit controllers C5 and C1, the circuit extending from the X terminal of the current source through contact 21—22 of controller C5, back contact 54 of controller C1 in the event the contactor 27 occupies 10 a position to the left of the constant speed point CP, back contact 79 of relay R^C, back contact 48 of relay R^A, armature 44, controller C10, back contact 47, back contact 80, back contact 53 of controller C1 and to the Y terminal of the current 15 source. The rotation of motor M¹ is now in a direction to drive the contactor 27 clockwise from its position to the left of point CP back to the constant speed point CP at which point the cam 26 lifts the member 74 to its center position to 20 open the controller C1 and remove current from the motor M¹. In the event the contactor 27 occupied a position to the right of the point CP, the front contacts 51 and 52 of controller C1 are 25 closed and the rotation of motor M¹ is in a direction to drive the contactor 27 in a counter clockwise direction back to the constant speed point CP where the controller C1 is shifted to its center position and motor M¹ deenergized. 30

In the event a second train should enter the 35 measuring section A—B before the first train has passed the highway H and vacated the track section D—E, the stick relay R^S will not be reenergized when the first train moves out of the section D—E. Under this condition, the pickup circuit 40 for relay R^S is held open at the front contact 32 of track relay R^A, that relay being shunted by the 45 second train occupying the section A—B. The front contact 43 of relay R^S being held open, operation of neither motor M¹ nor M² takes place 50 in response to the second train in the measuring section. The operating circuit for the mechanism M³ is now completed through the back contact 81 of relay R^S and hence operation of the 55 highway signal S is continued while the second train travels the successive track sections in approaching the highway H.

In the event a train is travelling in the reverse direction, that is, against the normal direction of traffic, and enters the track section D—E from 55 the right, the measuring devices remain inactive. Under this condition, the track relay R^D is first deenergized to open the front contact 36 in the stick circuit for relay R^S and that relay is released. The front contact 43 of relay R^S being 60 now open, the circuits for both motors M¹ and M² are not completed when the track relays R^A, R^B and R^C become deenergized, and hence neither the speed measuring device nor the acceleration-deceleration measuring device will function 65 while this train travelling in the reverse direction occupies the successive track sections.

If for any reason, the motor M² fails to operate, the contact member C6 will remain in engagement with the contacts 12 and 13, and the 70 signal S will be operated immediately when the train enters the operating section C—D to release the relay SR. The operating circuit now extends from terminal X along wire 12, back contact 71, contact 12—13 of C6, wire 73, mecha- 75

nism M^3 to the terminal Y. Again, if for any reason the motor M^2 is operated at an abnormally high rate of speed, the contact member C6 will be lifted into engagement with the contacts 5 14 and 15 and operation of the highway signal S will be immediately started as soon as the relay SR is deenergized.

It should be noted that in the event a train should stop in either of the measuring sections, 10 the motor M^2 would drive the shaft 6 around to its full reverse position where the depression 19 of the cam 7 mates with the member 18 and the controllers C8, C9 and C10 are all opened. This 15 operation of the controllers C8 and C10 opens the armature circuit for motors M^2 and M^1 , respectively, and the operation of the speed measuring device and of the acceleration-deceleration measuring device is stopped. Controller C9 opens the stick circuit for the relay R^S and that relay 20 is deenergized and will remain deenergized as long as the speed measuring device occupies this full reverse position. With relay R^S down, current is supplied to the mechanism M^3 of the highway signal S by the circuit completed at the 25 back contact 81 of relay R^S . When this train proceeds and enters the operating section C—D, the shunting of the track relay R^C will cause the speed measuring device and the acceleration-deceleration measuring device to be restored to 30 their respective normal position in the same manner as described hereinbefore. The relay R^S will not be reenergized until after the train has passed the highway, and hence the signal S will be operated to warn the highway users.

35 Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a stretch of railway track 45 intersected by a highway, a highway crossing signal located at the intersection; a speed measuring means, and an acceleration-deceleration measuring means and both governed by a train approaching the intersection; and means controlled jointly by the speed measuring means and the acceleration-deceleration means for starting the operation of said signal at substantially the same interval of time before the train reaches the intersection regardless of the speed and condition 50 of acceleration or deceleration of the train.

2. In combination, a stretch of railway track intersected by a highway, a highway crossing signal located at the intersection, a first measuring means governed by a train approaching said intersection and adapted to start the operation of said signal at substantially the same interval of time before the train reaches the intersection regardless of the average speed of the train, and 60 a second measuring means governed by a train approaching the intersection and adapted to control said first measuring means in such a manner as to start the operation of said signal at substantially the same said interval of time before the train reaches the intersection notwithstanding acceleration or deceleration of the train.

3. In combination, a stretch of railway track intersected by a highway, a highway crossing signal located at the intersection, a speed measuring means governed by a train approaching said 70

intersection for measuring the average speed of the train and adapted to start the operation of said signal at substantially the same interval of time before the train reaches the intersection for all measured speeds, and an acceleration-deceleration measuring means governed by a train approaching said intersection for determining the acceleration and deceleration of the train and adapted to control the speed measuring means in such a manner as to start the operation of 10 said signal at substantially the same said interval of time before the train reaches the intersection notwithstanding acceleration or deceleration of the train.

4. In combination, a stretch of railway track 15 intersected by a highway, a highway crossing signal located at the intersection, operating means for setting the signal into operation when a train approaching the intersection reaches a fixed point, a first device to register the speed of the 20 train as it approaches said fixed point, a second device to register the acceleration or deceleration of the train as it approaches said fixed point, and means controlled jointly by said two devices to retain the operating means ineffective to set 25 the signal into operation for a period determined by the registered speed and the registered acceleration or deceleration after the train reaches said fixed point.

5. In combination, a stretch of railway track 30 intersected by a highway, a highway signal located at the intersection, operating means for setting the signal into operation when a train approaching the intersection reaches a fixed point, a first device to register the average speed 35 of the train as it approaches said fixed point, a second device to register changes in the speed of the train as it approaches said fixed point, and means controlled jointly by said two devices to retain the operating means ineffective to set 40 the signal into operation for a period which depends upon both the registered speed and the registered change in the speed after the train reaches said fixed point.

6. In combination, a stretch of railway track 45 intersected by a highway, a highway crossing signal located at the intersection, a first device governed by a train approaching the intersection to measure the time interval required for such train to traverse a fixed distance, a second device governed by such train while traversing such fixed distance to register the difference between the time intervals required by the train to traverse the first and the second half of said fixed distance, and means controlled jointly by 50 55 said two devices for governing the operation of said signal.

7. In combination, a stretch of railway track intersected by a highway, a highway crossing signal located at the intersection, operating 60 means for setting said signal into operation when a train approaching the intersection reaches a fixed point; a time measuring means to measure the time interval required for a train approaching said fixed point to traverse a fixed distance, 65 and to determine the difference between the time intervals required by the train to traverse the first and the second half of said fixed distance; and means controlled by the time measuring means for delaying the operating means from 70 setting said signal into operation for a period which depends upon both the said measured time interval and the said determined difference in time intervals.

8. In combination, a stretch of railway track 75

intersected by a highway, a highway crossing signal located at the intersection, operating means for setting said signal into operation when a train approaching the intersection reaches a fixed point; a time measuring means to measure the time interval required for a train approaching said fixed point to traverse a fixed distance, and to determine the difference between the two time intervals required by the train to traverse two different given portions of said fixed distance; and means controlled by the time measuring means for delaying the operating means from setting the signal into operation for a period which depends upon both the said measured time interval and said determined difference in time intervals.

9. In combination, a stretch of railway track intersected by a highway, a highway crossing signal located at the intersection, operating means for setting said signal into operation when a train approaching the intersection reaches a fixed point; a time measuring means to measure the time interval required for a train approaching said fixed point to traverse a fixed distance, and to determine the difference between the two time intervals required by the train to traverse two different given portions of said fixed distance; means controlled by the time measuring means for delaying the operating means from setting the signal into operation for a period which depends upon both the said measured time interval and said determined difference in time intervals, and means for annulling the period of delay in the event of failure of the time measuring means.

10. In combination, a stretch of railway track intersected by a highway, a highway crossing signal located at the intersection, operating means for setting said signal into operation when a train approaching the intersection reaches a fixed point, a first time measuring means to measure the time interval required for a train approaching said fixed point to traverse a fixed distance, a second time measuring means to determine the difference between the two time intervals required by the train to traverse two different given portions of said fixed distance, and means controlled jointly by said two time measuring means for delaying the operating means from setting the signal into operation for a period which depends upon both said measured time interval and said determined difference in time intervals.

11. In combination, a stretch of railway track including a first and a second track section of substantially equal lengths, a signaling device, a time measuring means operated by a train passing through said track sections to register the difference in the time intervals required for a train to traverse said first and said second track sections and thereby determine the acceleration or deceleration of said train, and means controlled by said time measuring means to govern said signaling device in accordance with the determined acceleration or deceleration.

12. In combination, a stretch of railway track including a first and a second track section and each of a predetermined length, a signaling device, a time measuring means operated by a train passing through said track sections to measure the difference in the time intervals required for a train to traverse said first and said second track sections whereby the change in the speed of the train is registered, and means controlled by said time measuring means to govern the

signaling device in accordance with the change in the speed of the train.

13. In combination, a stretch of railway track intersected by a highway and divided into a measuring section and an operating section which a train traverses in the order named as it approaches the intersection, a highway crossing signal located at the intersection, operating means to start operation of said signal as a train enters the operating section, a first device to render the operating means ineffective to start operation of the signal for a period varying inversely with the average speed of the train in the measuring section, and a second device to decrease or increase said period in proportion to the increase or decrease in the speed of the train in the measuring section.

14. In combination, a stretch of railway track intersected by a highway and divided into a measuring section and an operating section which a train traverses in the order named as it approaches the intersection, a highway crossing signal located at the intersection, operating means to start operation of said signal as a train enters the operating section, a first device to render the operating means ineffective to start operation of the signal for a period varying inversely with the average speed of the train in the measuring section, and a second device to modify said period in proportion to the change in the speed of the train in the measuring section.

15. In combination, a stretch of railway track intersected by a highway, a highway crossing signal, a first member normally occupying one position, means for moving said first member away from said one position at a constant speed during the time interval required for a train approaching the highway to traverse a fixed distance, a second member normally occupying a given position, means for moving said second member in one direction away from said given position at a constant speed during the time the train travels the first half of said fixed distance and to move said second member in the opposite direction at said constant speed during the time the train travels the second half of said fixed distance, means effective when the train has traversed said fixed distance for restoring said first member to said one position at a speed which depends upon the position to which said second member has previously been moved, and means governed by said first member for controlling said signal.

16. In combination, a stretch of railway track intersected by a highway, a highway crossing signal located at said intersection, a member normally occupying one position, a first operating means effective for moving said member away from said one position at a constant speed during the time interval required for a train approaching the intersection to traverse a fixed distance, means to register the change in speed as the train traversed said fixed distance, a second operating means effective when the train has traversed said fixed distance for restoring said member to said one position at a speed which depends upon the registered change in speed, and means governed by said member for setting said signal into operation.

17. In combination, a stretch of railway track intersected by a highway, a highway crossing signal located at said intersection, a first member normally occupying one position, a first operating means effective for moving said member away from said one position during the time in-

terval required for a train approaching the intersection to traverse a fixed distance, a second member normally occupying a given position, a second operating means for moving said second member away from said given position in accordance with the change in the speed of the train in travelling said fixed distance, a third operating means effective when the train has traversed said fixed distance for restoring said first member to said one position in accordance with the position of said second member, means governed by said first member for controlling the operation of the signal, and means effective to restore said second member to said given position after operation of said signal is started.

18. In combination, a stretch of railway track intersected by a highway and divided into a measuring section and an operating section which a train traverses in the order named as it approaches the intersection, a highway crossing signal located at the intersection, operating means to start operation of said signal as a train enters the operating section, a speed measuring device controlled by a train in the measuring section for rendering the operating means ineffective to start the operation of said signal for a period in accordance with the speed of the train, and means including a stick relay effective to maintain operation of the signal irrespective of the speed measuring device when a second train enters the measuring section before a preceding train has vacated the operating section.

19. In combination, a stretch of railway track intersected by a highway and divided into a measuring section and an operating section which a train traverses in the order named as it approaches the intersection, a highway signal at the intersection, a speed measuring device controlled by a train in both the measuring and operating sections, an acceleration-deceleration measuring device controlled by the train in the measuring sections, means controlled jointly by said two devices for governing the operation of the signal, and circuit means operative in response to a train as it traverses said operating and measuring sections in moving away from the intersection for rendering both the speed measuring means and the acceleration-deceleration means inoperative.

20. In combination, a stretch of railway track over which traffic normally moves in one direction and intersected by a highway, a highway signal located at the intersection, a speed measuring device and an acceleration-deceleration measuring device both controlled by a train as it approaches said intersection in the normal direction of traffic, operating means controlled jointly by said two devices for governing the operation of said signal, and means responsive to a train traveling away from the intersection in a direction reverse to the normal direction of traffic to render both the speed

measuring device and the acceleration-deceleration measuring device ineffective to govern said signal.

21. In combination, a stretch of railway intersected by a highway, a highway crossing signal located at the intersection, operating means governed by a train for setting the signal into operation when the train reaches a fixed point to the rear of the intersection, a speed measuring means, an acceleration measuring means, means governed by the train approaching the fixed point for operating said speed measuring means and said acceleration measuring means, means controlled by the speed measuring means to render the operating means ineffective to start operation of the signal for a period varying inversely with the measured speed of the train, and means controlled by the acceleration measuring means to correct said period in proportion to the acceleration of the train. 20

22. In combination, a stretch of railway intersected by a highway, a highway crossing signal located at the intersection, operating means governed by a train for setting the signal into operation when the train reaches a fixed point to the rear of the intersection, a speed measuring means, an acceleration and deceleration measuring means, means governed by the train approaching the fixed point for operating said speed measuring means and said acceleration 30 and deceleration measuring means, means controlled by the speed measuring means to render the operating means ineffective to start operation of the signal for a period varying inversely with the measured speed of the train, and means controlled by the acceleration and deceleration measuring means to correct said period in proportion to the acceleration or deceleration of the train. 35

23. In combination, a stretch of railway track intersected by a highway, a highway crossing signal located at the intersection, a speed measuring means, an acceleration-deceleration measuring means, means governed by a train approaching the intersection for operating said speed measuring means and said acceleration-deceleration measuring means, operating means controlled jointly by the train and said speed measuring means for starting the operation of the signal a predetermined interval of time prior to arrival of the train at the intersection regardless of the speed of the train, and means controlled by the acceleration-deceleration measuring means to correct the time of starting operation of the signal in proportion to the acceleration or deceleration of the train to assure said predetermined interval of operation when the train is accelerating or decelerating. 40 45 50 55
